The ornamental design for a broom, as shown and described.

DESCRIPTION

FIG. 1 is a front elevation of the broom of the invention.

FIG. 2 is a top view of the broom of the invention.

FIG. 3 is a side view of the broom of the invention; and, FIG. 4 is a view of the other side of the broom of the invention.

The rear of the broom is a mirror image of the front shown in FIG. 1 and the bottom of the broom forms no part of the claimed design.

The broken lines showing a handle are for illustrative purposes only and form no part of the claimed design.
